BENJAMIN A. MITCHELL, OF GARFIELD, UTAH.

VIBRATING SCREEN.

Application filed September 30, 1920. Serial No. 413,844.

To all whom it may concern:

Be it known that I, BENJAMIN A. MITCHELL, a citizen of the United States, residing at Garfield, in the county of Salt Lake and State of Utah, have invented certain new and useful Improvements in Vibrating Screens, of which the following is a specification.

This invention relates to improvements in vibrating screens and its purpose is to provide screening apparatus having improved means for mounting the screen cloth and imparting vibrations thereto.

The principal object of the invention is to provide a screening machine in which the screening medium is supported entirely by the vibrator. A further object is to provide a screening machine having a plurality of screening units which are vibrated simultaneously but out of phase with each other. Still another feature is the provision of a screening machine comprising improved means for supporting the screening medium and for creating minute vibrations therein which describe closed paths in planes perpendicular to the screening medium. Other objects relate to various features of construction and arrangement which will appear more clearly hereinafter.

30 The nature of the invention will be understood from the following specification taken in connection with the accompanying drawings in which two embodiments are illustrated.

35 In the drawings—

Figure 1 shows an end elevation of one form of the improved screening machine, the walls of the feeding hopper and of the chamber for receiving the materials to be screened being shown in section;

40 Fig. 2 shows a perspective view of the under side of the screening machine, a portion of the supporting frame being broken away;

45 Fig. 3 shows a perspective view of the screening machine looking downwardly toward the upper side thereof;

50 Fig. 4 shows a longitudinal sectional view through the vibrator employed, the section being taken on the line 4—4 of Fig. 1;

55 Fig. 5 shows a vertical section on the line 5—5 of Fig. 4;

Fig. 6 shows a longitudinal sectional view through a modified form of the screening machine in which the screening medium is

mounted as a single unit, the rotary vibrator and a portion of the supporting frame being shown in elevation; and

Fig. 7 shows a transverse sectional view on the line 7—7 of Fig. 6.

60 The screening machine as illustrated in Figs. 1 to 5, inclusive, comprises a supporting frame having a transverse frame member 10 formed integrally with two side frame members 11 which are parallel to each other. The side frame members are provided at their upper ends with projecting pins 12 adapted to engage sockets 13 in supporting brackets 14 which are secured to the vertical wall 15. The lower ends of the side frame members 11 are provided with enlarged bosses 16 having threaded apertures extending vertically therethrough. These apertures are engaged by adjusting screws 17 which are arranged with their lower ends 70 seating upon a supporting plate 18 carried by the upper edge of the wall 19. The wall 19 is spaced from the wall 15 to form an intermediate chamber 20 adapted to receive the screened materials which pass through 75 the screening apparatus carried by the supporting frame 10. The adjusting screws 17 may be secured in position by lock nuts 21, thereby maintaining the supporting frame 80 at any desired angle.

85 The loose materials such as crushed ore, coal, gravel, or the like, which are to be screened are distributed onto the screening medium from a discharge chamber 23 which is mounted along the upper edge of the 90 wall 15. The materials are discharged in a thin stream throughout the length of the screening machine, as shown at 24, by means of a rotary screw conveyer 25. The crushed materials are discharged onto the screw conveyer 25 and into the discharge chamber 23 from a hopper 26.

95 The screening machine is vibrated by means of the vibrator designated generally by the numeral 30. This vibrator has a casing 31 which consists of an enlarged central portion 31^a and two projecting end portions 31^b of reduced diameter. The vibrator casing extends parallel to the frame member 10 and is supported thereby, being secured 100 thereto through a strap 32 which extends around the central part of the enlarged portion 31^a of the casing. This strap is provided at its ends with threaded bolts 33 which engage ears 34 formed integrally with 110

the frame member 10 on opposite sides thereof. The ends of the bolts 33 are engaged by nuts 35 which may be adjusted in order to regulate the pressure with which the 5 vibrator casing is held in position on the frame member. The central part of the vibrator casing is provided with a projection 36 which carries a cap 37 having a substantially spherical surface formed thereon 10 and adapted to seat in a corresponding recess formed in the upper part of the frame member 10 so that a limited vibratory movement of the casing 31 is permitted, depending upon the degree of tension in the holding strap 32.

The vibrator casing is formed in two sections, as shown particularly in Fig. 4, and the two parts are secured together by means of elongated bolts 38 which extend through 20 the enlarged portions 31^a of the casing and through apertures which are formed in the end walls 31^c by which the central part of the casing is connected to the projecting end portions 31^b. A longitudinal shaft 40 extends throughout the vibrator casing and is journaled in bearings formed in the bearing members 41. These bearing members have enlarged parts 41^a, which occupy the end portions of the enlarged casing 31^a, and 25 other reduced portions 41^b which project into and closely fit the reduced parts 31^b of the casing. The bearings for the shaft 40 are formed in the reduced parts 41^b and these portions are provided with oil receiving 30 recesses 42 from which oil is supplied to the shaft 40 by oil rings 43. The vibrator shown is driven by an electric motor the field frame and pole pieces 45 of which are mounted in position between the central 35 parts 41^a of the bearing members and the armature 46 of the motor is secured on the central part of the shaft 40. Apertures 47 are provided through the bearing members and through the casing to permit the necessary 40 ventilation of the motor.

This vibrator utilizes the principle of rotating moments to produce vibrations as set forth in my copending application, Serial No. 275,321. To this end bodies whose average mass center is eccentric to the axis of rotation are employed. Accordingly there is provided roller cages 50 which are secured respectively at each end of the shaft 40 each being mounted between one of the bearing 50 members 41^b and the end wall 51 of the casing 31. Each cage 50 is provided on diametrically opposite sides with a series of recesses 52 which are circular in cross section and arranged in a row parallel to the axis of 55 the shaft 40. One row of recesses 52 in each cage 50 is adapted to contain a series of spherical balls 53 which travel around with the rotation of the cage and engage annular raceways 54 of hardened metal which are secured within the casing and hollowed out on 60

their inner sides, as shown at 55, to form a separate annular track for each spherical ball. The balls 53 in one cage are preferably arranged on the opposite side of the shaft 40 from the balls in the other cage. As the 70 shaft is rotated at a comparatively high speed, preferably about 3600 revolutions per minute, the balls 53 are carried around in their raceways by the cages 50 and the effect of these rapidly rotating balls located 75 eccentrically with respect to the axis of the shaft 40 is to cause each particle of the casing 31 to travel in a minute closed path. As will be observed, the vibrations in the opposite ends of the casing 31 are displaced in 80 phase from each other by substantially 180 degrees. The end portions of the casing are preferably filled with oil in order to reduce the friction created by the rotation of the spherical balls.

The vibrations thus set up in the vibrator casing are transmitted to the screening medium through transmitting members 60. In the form of the invention illustrated in 85 Figs. 1, 2, and 3, these transmitting members comprise arms 61 which diverge upwardly from collars 62. These collars are adapted to fit the tapered end portions 63 of the vibrator casing 31 and they are secured in position thereon by transverse keys 64 which engage keyways in the projecting end flanges 65 of the vibrator casing. Each arm 61 carries at its upper end a transversely extending channel member 66, the channel members carried by opposite transmitting members 60 being arranged in alinement with each other. A screen frame 67 is carried by each transmitting member 60, each frame comprising wooden side frame members 68, end frame members 69, and a central transverse frame member 70. The end frame members 69 are seated in the channel members 66 and are secured thereto by bolts 71. The side frame members 68 are secured to the end frame members 69 by angle plates 72 and bolts 73. The central transverse frame members 70 are secured to the side frame members 68 by angle plates 74 and bolts 75. Two rigid frame members 67 of 90 wooden construction are thus formed and each frame is supported independently of the other on one of the transmitting members 60 so that each particle of each screen frame is vibrated in a closed path out of phase with the vibrations of the other frame. The woven wire screen cloth 77 is secured to each frame 68 by means of a series of double pointed tacks 78 which engage the wooden frame members, thus holding the screen cloth in a taut condition on the supporting frame. As the vibrator is operated and the crushed materials are passed downwardly thereover, they are thoroughly screened by the action of the screen cloth, 95 each particle of which describes with sub- 100

stantially uniform amplitude the path of the orbit of the transmitted vibration in a plane which is perpendicular to the plane of the screen frame and also perpendicular to the axis of the rotary vibrator, but parallel to the path of travel of the crushed materials over the screening medium. The inclination of the screening medium can be regulated by changing the angle of the supporting frame through the manipulation of the adjusting screws 17, and by regulating the angle of the screen cloth and the speed with which the crushed materials are fed to the screen surface, it is possible to effect a very efficient screening of the crushed materials before they reach the lower edge of the screen.

A modified form of the invention is illustrated in Figs. 6 and 7 where the vibrator 80 is secured by a strap 81 to a transverse frame member 82 which may be similar to and mounted in the same way as the supporting frame heretofore described. The projecting ends 80^a of the vibrator, in which the minute circular vibrations are set up, carry transmitting members 83 comprising plates 84 which have apertures 85 therein adapted to be closely fitted by the end portions 86 of the vibrator casing. These plates are secured in position by keys 87 and the upper edges thereof are secured by rivets 88 to the side plates 89. These side plates extend upwardly and outwardly from the plates 84, as shown at 89^a and terminate in parts 89^b of angle form which are reinforced along their upper edges by angle irons 90. A screen frame 91 is adapted to seat in the angle members 89^b, as shown in Fig. 6, this screen frame comprising wooden side frame members 92 connected by transverse end members 93 of wooden construction. These members are rigidly secured at their intersections and are connected to the supporting members 89^b by means of bolts 94. The screen frame 91 also comprises a number of intermediate frame members 95 which extend between the end frame members 93. The lateral spreading of the transmitting members 84 is prevented by a transverse tie rod 96 which is secured to the frame by bolts 97 and connected to the side plates 89 by bolts 98. The wooden frame 91 is thus mounted securely on the metallic frame and is carried entirely by the rotary vibrator. The screen cloth 100 is mounted on the wooden frame 91, being secured to the frame members by means of double pointed tacks. When the vibrator is operating, two sets of vibrations displaced in phase from each other are set up in the screen cloth. This form of the invention and the one previously described are particularly adapted for screen cloth of relatively fine mesh since the cloth is rigidly supported in a taut condition and is effectively vibrated without the necessity

of setting up any substantial degree of tension therein.

Although I have shown and described certain embodiments of the invention for purposes of illustration, it will be understood that it may be constructed in various other forms without departing from the scope of the appended claims.

I claim:—

1. In a screening machine, the combination with a vibrator having a casing adapted to execute vibration in paths forming closed orbits, of a plurality of supporting devices respectively mounted on different parts of said casing, and screens on each of said devices. 75

2. In a screening machine, the combination with a vibrator having a casing centrally mounted and provided with projecting ends adapted to execute harmonic motion in planes transverse to the axis of symmetry, of supporting devices respectively mounted on the ends of said vibrator and arranged to be in different phases when said vibrator is in motion, and screens carried by each of said devices. 85

3. In a screening machine, the combination with a vibrator having a casing centrally mounted and provided with projecting tubular ends adapted to be internally actuated to execute harmonic motion in planes perpendicular to the axis of symmetry, of supporting devices mounted respectively on each end of said vibrator and arranged to be in different phases when said vibrator is in motion, a screen frame carried by each of said devices, and a screen secured in each screen frame. 95

4. In combination, a vibrator, a pair of transmitting members secured thereto, a pair of screen frames each mounted independently on one of said transmitting members, and a screen cloth mounted on each of said frames. 105

5. In combination, a vibrator, a pair of transmitting members secured thereto, a pair of screen frames each mounted independently on one of said transmitting members, a screen cloth mounted on each of said frames, and means for operating said vibrator to vibrate said frames simultaneously and out of phase with each other. 110

6. In combination, a vibrator casing, means for producing rotary vibrations in the ends of said casing, transmitting members extending from said casing, a pair of screen frames each mounted independently on one of said transmitting members, and a screen cloth mounted on each of said frames. 115

7. In combination, a vibrator, means for producing vibrations having different phase relations in different parts of said casing, transmitting members extending from the different parts of said casing, a screen frame mounted on each of said transmitting members. 125

- bers, and a screen cloth mounted on each of said frames.
8. In combination, a vibrator, means for producing vibrations having different phase relations in different parts of said casing, transmitting members extending from the different parts of said casing, a screen frame mounted on each of said transmitting members, a screen cloth mounted on each of said frames, means for supporting said vibrator, and means for changing the inclination of said support to vary the inclination of said screens.
9. In combination, a supporting frame, means for pivotally supporting one edge of said frame, means for adjustably supporting the opposite edge of said frame, a vibrator mounted on an intermediate part of said frame, and a screen carried by said vibrator.
10. In combination, a supporting frame, means for pivotally supporting one edge of said frame, means for adjustably supporting the opposite edge of said frame, a vibrator mounted on said frame with its axis parallel to the axis of movement of said frame, transmitting members secured to said vibrator and extending transversely thereto, a screen frame carried by each of said transmitting members, and a screen cloth mounted on each of said frames.
11. In combination, a supporting frame, means for pivotally supporting one edge of said frame, means for adjustably supporting the opposite edge of said frame, a vibrator mounted on said frame with its axis parallel to the axis of movement of said frame, transmitting members secured to said vibrator and extending transversely thereto, a wooden screen frame mounted in an inclined position on each of said transmitting members, and a screen cloth tacked on each of said wooden frames.
12. In combination, a supporting frame, means for pivotally supporting one edge of said frame, means for adjustably supporting the opposite edge of said frame, a vibrator mounted on said frame with its axis parallel to the axis of movement of said frame, transmitting members secured to said vibrator and extending transversely thereto, a wooden screen frame mounted in an inclined position on each of said transmitting members, a screen cloth tacked on each of said wooden frames, and means for causing loose materials to pass downwardly over said screen cloth to planes perpendicular to the axis of said vibrator.

In testimony whereof, I have subscribed my name.

BENJAMIN A. MITCHELL.
